UNITED STATES PATENT OFFICE.

WILLIAM L. PANIKOFF, OF NEW HAVEN, CONNECTICUT.

BADGE OR INSIGNIA.

Application filed February 27, 1922. Serial No. 539,367.

To all whom it may concern:

Be it known that I, WILLIAM L. PANIKOFF, a citizen of the United States, residing at New Haven, in the county of New Haven and State of Connecticut, have invented a new and useful Improvement in Badges or Insignia; and I do hereby declare the following, when taken in connection with the accompanying drawings and the characters of reference marked thereon, to be a full, clear, and exact description of the same, and which said drawings constitute part of this application, and represent, in—

Fig. 1 a front view of badge or insignia constructed in accordance with my invention, and shown with three insignia plates attached thereto.

Fig. 2 a sectional view, on the line 2—2, of Fig. 1.

Fig. 3 a perspective view of one of the insignia plates detached.

Fig. 4 a sectional view, illustrating a modified form of attaching insignia plates.

Fig. 5 a sectional view, illustrating another method of attaching insignia plates.

This invention relates to improvement in badges or insignia particularly designed as a badge for sportsmen. The object of the invention is to provide a badge with a series 30 of sections, in each of which a different insignia may be placed, and the invention consists in the construction as hereinafter described and particularly recited in the claim.

In carrying out my invention, the badge 35 consists of a backing 6 of any approved design, provided with a series of panels 7, in each of which insignia plates 8 may be placed. It is obvious that these panels may be square, as shown, or round, or oval, or 40 of any other design. The insignia plates 8 may be secured in position in a variety of

ways; thus, as shown in Fig. 1 of the drawings, the panels may be provided with slots 9; or, as shown in Figs. 2 and 3 of the drawings, the insignia plates 8 may be formed 45 with prongs 10 adapted to be passed through the slots 9 and turned down upon the inside; or, as shown in Fig. 4 of the drawings, the insignia plates 8 may have clips 11 to pass through the centrally-arranged slots 12 in 50 the bar; or, if desired, the edges of the bar may be formed with ears 13, adapted to be turned over the back of the insignia plates, in which case the panels may be formed with a sight-opening 14, as shown in Fig. 5 of 55 the drawings.

The device is adapted to be used, for instance, in the following manner: A league is formed, and each member secures a bar. Then, from time to time, as they make a pre-determined record in any particular sport, 60 they secure an insignia plate indicating that sport, and attach this insignia plate to the bar, and this is continued until all of the spaces in the bar are filled. It is understood 65 that the number of spaces provided may vary according to the circumstances.

I claim:

A badge or insignia comprising a bar formed with a series of panels, each panel 70 formed with slots, and a series of individual insignia plates, each formed with prongs adapted to be passed through said slots, whereby the said plates are individually secured in the said panels. 75

In testimony whereof, I have signed this specification in the presence of two subscribing witnesses.

WILLIAM L. PANIKOFF.

Witnesses:

FREDERIC C. EARLE,
MALCOLM P. NICHOLS.
